METHOD OF AND APPARATUS FOR DRYING
MOVING MATERIAL

Carl G. Muench, New Orleans, and George H. Burt, Metairie, La., assignors to The Celotex Corporation, Chicago, Ill., a corporation of Delaware

Application January 16, 1939, Serial No. 251,064

13 Claims. (Cl. 263—40)

This invention relates to a method of and apparatus for drying sheets of artificial heat insulating lumber, preferably formed by the felting of bagasse fiber along with other materials necessary to make a satisfactory structural fiber board. This invention not only relates to the drying of the sheets, but in particular relates to the thermal economy of a drying system.

The principal object of the invention is to provide a drying system particularly for drying of fiber insulating board and the like.

Another object of the invention is to provide for rapid drying by high temperature water vapor, particularly super-heated water vapor, so that the drying can be carried on at a high temperature.

Another object of the invention is to combine a steam plant with a novel drying system so that the thermal efficiency of both systems is increased.

Another object of the invention is to provide a novel heat exchanger or air and water vapor mixture heater wherein the flue gasses for heating the heat exchanger are tempered by the waste gases therefrom. In describing this invention, from time to time the heat exchanger or air and water vapor mixture heater will be referred to merely as an "air heater" or "the air heater," and the atmosphere of super-heated steam, which, as hereinafter explained, normally includes a content of air, is hereinafter from time to time generally referred to merely as "air" or "the air," since this terminology, by merely thinking of the circulation of the drying medium as that of a simple gas, simplifies the terminology used in explaining the invention.

Still another object of the invention is to provide a novel method of controlling the thermal efficiency of a heating system comprising a steam plant and a drying system.

Another object of the invention is to provide a novel method of controlling the temperature within a drying system wherein combustion products at a temperature of substantially 3300° F. are tempered to 1200° F. by recirculating a portion of the waste gases from the air heater at a temperature of substantially 700° F. By this method, the resulting hot air or super-heated water vapor is discharged from the air heater for the drier at a temperature of substantially 700° F., and it is reduced within the drier from substantially 700° F. to substantially 350° F. by the material which is conveyed through the drier to be dried. The air is then returned to the air heater at substantially 350° F. to be reheated and recirculated.

A particular feature for improving the thermal efficiency of the combined steam plant and drier system is to pass the waste products from the steam plant and the drying system through an economizer.

Another feature of the invention is to provide the novel heat exchanger with a mixing chamber so that the hot flue gases are tempered by the waste gases from the air heater.

Another feature of the invention is to provide a drier wherein the hot drier gases preferably super-heated water-vapor are circulated in a substantially closed system, the super-heated water-vapor being heated in the air heater and discharged in the direction of travel of the fiber board which is being dried; and, as the drier system is a closed system, the expansion due to the evaporation of water from the board is suitably relieved by a vapor vent stack at the end of the drier.

With these and other objects in view, the invention consists of the novel steps and combination of steps constituting the process and in the novel parts and combination of parts constituting the apparatus, all of which will be more fully hereinafter disclosed and particularly pointed out in the claims.

Referring to the accompanying drawings forming a part of the specification in which like numerals designate like parts in all of the views,

Figure 1 is a plan view illustrating the novel drying system together with the steam plant combined therewith;

Figure 2 is an elevation along line 2—2 of Figure 1 looking in the direction of the arrows and particularly showing the mixing chamber in detail;

Figure 3 is a side elevation of a steam plant comprising the economizer looking along line 3—3 of Figure 1 in the direction of the arrows;

Figure 4 is a partial sectional view along the line 4—4 of Figure 1 looking in the direction of the arrows and illustrating the return air duct from the drier together with a section through the drier; and,

Figure 5 is a partial sectional view along the line 5—5 of Figure 1 looking in the direction of the arrows and illustrating the air heater together with the duct from the air heater to the drier for the incoming superheated air or water-vapor.

In order that the invention may be better understood, it is said; this invention is especially adapted for drying the wet sheets of heat insulating artificial lumber such as those that are now made from bagasse fiber and mixed with fibers derived from wood and known to the trade as Celotex brand cane fiber insulation.

The mixture of fibers are first passed over a sheet forming machine (not shown) which forms them into a sheet of a width of about ten or twelve feet. The sheet is then passed through the drier of this invention in continuous lengths; and, it is preferable, however, that the sheets from the sheet forming machines are cut into

suitable lengths so that the length of a drier will not be as long as in prior driers of this type, such as disclosed in the U. S. Patent to T. B. Munroe 1,598,980, granted September 7, 1926. The thickness of the finished sheet from the drier is about one-half inch; and, after being dried, it is cut up into boards of any desired dimensions. In practice, it is found that if the heat insulating artificial lumber or Celotex fiber sheets are made up from bagasse fibers alone, the said sheets are apt to dry unevenly, to warp, and to require a relatively long drying period for a desired product, thus reducing the output of the mill. If it is attempted, on the other hand, to speed up the commercial production of these sheets, as by increasing the temperature of the air employed in the drier, it is found that before any substantial practical results can be obtained, the air will have to be so hot as will unavoidably scorch the outer surfaces of the drying sheets, so that the latter will be injured, and the drying will also be found to be still uneven and to give rise to an objectionable warping of the finished sheets.

In addition to this, the felted fiber sheets are highly insulating in their properties and are provided with greater or less quantities of water repellent or waterproofing materials usually in the form of an aluminum resinate or other well known water resisting compound or repellent, and when air is employed as the drying medium or fluid, it is found that heat insulating water resisting layers are readily formed at the outer surfaces of the sheets in the drier while the interior portion of the sheets have a relatively large percentage of their original water still present. In fact, these layers retard the heat in reaching the interior, and retard the water there present in reaching the exterior of the sheets.

On the other hand, it is found that if the original bagasse fibers are admixed with a percentage of other fibers derived from wood, such for example as the waste wood fibers from a paper mill, or if disintegrated or ground up paper stock, is admixed with the bagasse fibers, the drying action itself becomes more even and satisfactory. So long as air is used as a drying medium, even if at a temperature above 250° F., or is heated up to a temperature of about 300° F., 350° F. or higher, which it is very desirable to do, if a high speed of drying is to be attained, the surfaces of the cane fiber sheets will still have the objectionable heat insulating and water resisting layers, and will still be scorched to an objectionable extent, although the drying action may be free from warping.

It is found that if the above mixture of bagasse fibers and fibers derived from wood is provided in the first place and if the formed cane fiber insulating sheets are subjected to steam at temperatures of say from 215° F. to 350° F. or higher, the sheets are found to dry very rapidly without scorching or warping and a very satisfactory quality and quantity of the product is produced. We are unable to satisfactorily explain the marked advantages of steam over air as a drying medium for these sheets, but have observed that steam especially at high temperatures does not produce the above water resisting layers on the surfaces of the sheets, but seems to penetrate throughout the interiors thereof, and to efficiently remove the water present by evaporating it. Apparently the sheets do not dry from the surfaces, and

because of the steam dry substantially uniform throughout. In order, however, to employ super-heated steam efficiently, it is preferable that the air should be substantially excluded from contact with the sheets, for at the temperatures mentioned any free oxygen present is liable to produce an objectionable scorching of the sheets and sometimes a fire in the drier which is impossible when steam is used.

Accordingly, in carrying out this invention, we provide a drier construction which is substantially air and steam tight, except at its ends where the fiber sheets enter and leave the drier. It is obvious that the drier may be several hundred or a thousand feet long or longer if necessary to satisfactorily dry the sheets within the drier. In this particular drier, however, the length of the drier is only about one hundred fifty feet.

Since the sheets which are being dried are about $\frac{1}{2}$ " in thickness, it is found that it is not necessary to seal the inlet and exit end of the drier, although said ends may be more or less sealed by flaps of canvas against the escape of the steam if so desired.

Without referring by number to the parts and elements involved, a brief disclosure of the units making up the machine will be given to show the general arrangements of parts and their cooperation with each other. In a plant for the manufacture of insulating board of this type, it is necessary that there be had a great deal of steam and hot water for processing. Therefore, a novel steam plant is provided with the additional heat saving device employed with a steam plant, and in this particular instance takes the form of an economizer or water heater placed in the draft stack of the steam boiler plant. By so using an economizer, the thermal efficiency of the steam plant is very much increased. To further increase the thermal efficiency of our combined steam plant and novel drying system of our invention, our novel drying system is also adapted to be connected to the economizer.

The novel heating or drying system of our invention comprises a furnace for supplying the hot gases of combustion which are preferably discharged into a hot gas chamber at a temperature of substantially 3300° F. The hot gases of combustion are then discharged into a mixing chamber where they are tempered to a temperature of substantially 1200° F. The tempered gases are then led through a suitable heat exchange means where they heat the air or super-heated steam, for drying, to a temperature of 700° F. The waste flue gases are then partially discharged through the economizer and the remaining portions are discharged into the mixing chamber where they are used to temper the incoming hot products of combustion. If necessary cool air may also be by-passed into the mixing chamber for further tempering the gases. As the waste flue gases from the air heater are discharged into the economizer or water heater, it is evident that the combined thermal efficiency of the steam plant and the drying system is materially increased.

The heated air at a temperature of 700° F. is then discharged into the novel drier at one end thereof and preferably in the direction of travel of the sheets to be dried. Although the conveying means have not been shown in detail for conveying the sheet through the drier, it is

obvious that the conveying means may take any form of suitable conveyor from the prior art. We prefer, however, to use the type of conveying apparatus as disclosed in the U. S. Patent 1,598,980 granted to T. B. Munroe, September 7, 1926, adapted for a multiple deck drier. Since the temperature of air is 700° F. coming from the air heater, it is obvious that the water within the sheet is rapidly dried therefrom, with the result that the air within the drier becomes substantially saturated water-vapor and super-heated; and, as the process is a continuous one it is obvious that the resultant drying of a sheet is effected by the use of super-heated water-vapor or super-heated steam, so that the sheets being dried within this drier are dried evenly and without warping. As the tiers of sheets being dried travel down through the drier, it is evident that the temperature within the drier is substantially reduced; and, at the end where the sheets leave the drier, the temperature of the steam within the drier is reduced to a temperature of 350° F. As our novel drying system is of the type known as a closed system, the expansion due to the evaporation of the water from the board must be released, and this is accomplished by a vapor vent stack at the end of the drier from which the sheets which are dried leave.

The super-heated steam now reduced at the end of the drier to a temperature of 350° F. is then divided and returned alongside on each side of the center drying duct counter to the direction of travel of the board. The steam and air at a temperature of 350° F. is then preferably discharged into the air heater where it is reheated to a temperature of 700° F. to be recirculated through the drier.

The gas or super-heated steam that does the drying does not come in contact with the combustion gases within the air heater at any time. Super-heated steam is recirculated from the air heater to the drier and back again at a predetermined rate so that the incoming sheets to the drier when they leave the drier are thoroughly dried. The air or gaseous medium within the drying system after the starting period quickly progresses from air to water-vapor and to super-heated steam and theoretically would be water vapor only for drier operation. Since this drier system is operating at substantially atmospheric pressure, it is evident that the water vapor within the drying system would be highly super-heated.

An emergency damper is provided at the outlet of the hot gas chamber to protect the air heater and other equipment in case the fans should stop. The damper is suitably controlled by thermostatically operated devices placed in strategic points within the drier and air heater.

In the drawings, Figure 1 shows the essential elements of our novel drying system and steam plant. The novel steam plant of our drying system will now be described. A suitable boiler 10, since in this case a large volume of low temperature steam and hot water are needed, is of the general type of Scotch Marine boiler and is preferably mounted on a setting 11. The boiler 10 is fired from bunker 12 by suitable stokers indicated at 13.

The combustion gases from the boiler 10 pass to a boiler flue 14, and the gases are preferably discharged at a temperature of 800° F. The combustion gases enter an economizer chamber 15 and are deflected by a baffle 16 across an economizer or water tubes 17. The water tubes 17

form a suitable water heater, and the water within this water heater is heated to a temperature of preferably 180° F.

As best illustrated in Figures 1 and 3, the hot products of combustion as they leave the water heater 17 are discharged downwardly into a flue 18. Depending upon whether the temperature of the discharged gases is suitable to provide a natural draft, the gases are then discharged into the stack 21 directly. If the natural draft is not sufficient, an induced draft is produced by an induced draft fan 20; and, a damper 19 is set in duct 18, as illustrated in Figure 3, to cause the combustion products to discharge through bypass flues 22 and 23 into the stack 21. The fan 20 is adapted to be driven by a suitable motor 24. In order to have the steam plant operate at its maximum efficiency, it is preferable that the combustion gases are discharged into the stack 21 at a temperature of substantially 400° F.

We will now describe in detail the novel heating or drying system of our invention which is adapted to operate conjointly with the steam plant or separately therefrom. Similarly, the steam plant is also adapted to operate conjointly with the heating or drying system or separately therefrom. Referring to Figures 1 and 2, furnaces 30 are suitably fired from coal bunkers 31 by stokers 32. The hot products of combustion from the furnaces 30, as best illustrated in Figure 5, are discharged into a hot gas or combustion chamber 33 and are preferably at a temperature of 3300° F. The combustion products at a temperature of 3300° F. are discharged into a mixing chamber 34 which may be controlled by a damper 35. The combustion chamber 33 is also adapted to discharge to the atmosphere through a suitable by-pass chimney 36 which is also controlled by a damper 37. The by-pass chimney 36 is only used in case of emergency or when it is not desired to operate the drier or to control the amount of hot gases discharged into the mixing chamber 34. With the damper 37, as indicated in Figure 5, substantially closing the by-pass chimney 36, the hot combustion products discharge into the mixing chamber when the damper 35 is open. The damper 35 is an emergency damper and is open at all times except when the temperature within the air heater and drier becomes excessive. Then, the damper which is thermostatically operated is adapted to close so that the hot products of combustion are bypassed through the by-pass chimney 36 as the damper 37 is simultaneously opened. Generally, the temperature within the air heater and drier becomes excessive when the fans, which are to be described later, stop.

The hot products of combustion at the temperature of 3300° F. are tempered within the mixing chamber 34, i. e., reduced in temperature from 3300° F. to 1200° F. by admitting waste products of combustion or fresh air to the mixing chamber 34. The cool combustion gases for tempering the hot combustion gases are admitted into the mixing chamber 34 through cool combustion gas inlets 38. Referring to Figures 1, 2 and 5, the inlets 38 are connected to a flue 39 which is suitably connected to the heat exchanger or air heater 40 so that a portion or all of the hot waste gases from the heat exchanger or air heater are adapted to be returned to the mixing chamber. As the products of combustion which have been tempered by the waste gases from the air heater 40 to a temperature of 1200° F. pass down across the means for heating the air within the air heater,

the hot gases are reduced from 1200° F. to substantially 700° F. as they enter the waste gas flue 41. The air heater is so constructed that the gas, air or super-heated steam that is circulated for drying does not come in contact with the combustion gases at any time. The air or water vapor as it leaves the air heater is super-heated to a temperature of 700° F. and is recirculated from the heater to the drier and back again.

The waste gas flue 41 is adapted to be connected from the heat exchanger 40 or air heater, to the economizer or water heater 17 of the steam plant, and is also adapted to be connected by the flue 41 to the mixing chamber 34 so that a portion of the waste flue gases may be used to temper the hot combustion products from the hot gas chamber. A cool combustion gas return flue 42 is adapted to be connected to the waste gas flue 41 and is provided with a cold air inlet 43 having a damper 44 for suitably controlling the cold air inlet or means for supplying cold air 43. The function of the cold air inlet 43 is to provide cold air, if required, in sufficient amounts to additionally temper the waste flue gases from the air heater 40 before they enter the mixing chamber 34.

In order to temper the hot products of combustion from the hot gas chamber 33 as they enter the mixing chamber 34, it is within the scope of our invention that we may temper these hot gases either solely by the waste flue gases from the air heater 40, or by combining the waste flue gases with cold air or by cold air alone. A fan 45 circulates the gases for tempering the hot products of combustion from the waste gas flue 41 through the flue 42 to where it is connected to the duct 39 and from there into the mixing chamber 34. The fan 45 is adapted to be driven from an electric motor 46.

We prefer to so operate our air heater that the hot gases of combustion from the hot gas chamber 33 are reduced in temperature from 3300° F. to 1200° F. in the mixing chamber 34. We accomplish this by returning a portion of the waste flue gases from the air heater at a temperature of 700° F. to the mixing chamber 34. The proportion of hot gases at 3300° F. and waste flue gases at 700° F. are such that the resultant temperature of the gases leaving the mixing chamber 34 is reduced to 1200° F. It is also within the scope of our invention that the temperature of the gases may be tempered in the mixing chamber solely by the use of cold air or by the mixture of cold air and waste flue gases. The remainder of the flue gases from the air heater 40 which are not used to temper the gases in the mixing chamber 34 are led by the duct 41 to the economizer chamber 15 where they are then distributed through the economizer or water heater 17.

These waste flue gases from the air heater 40 are discharged into the economizer chamber 15 at a temperature of 700° F. and the amount of gases passing through the flue 41 are suitably controlled by a damper 47. By utilizing these waste flue gases from the air heater 40 by passing them through the economizer 17, it is obvious that the thermal efficiency of the drier system is materially increased. Similarly, the overall thermal efficiency of the steam plant and the drier system is also increased. Since the waste gas flue 41 of the air heater and the waste gas flue 14 of the steam plant are connected and controlled by dampers, and as each system, i. e., the steam plant and the drier system, have stacks

21 and 36, it is also obvious that both of these systems may be used together or independently.

The air or super-heated steam within the closed system of our drier is rapidly circulated by a fan 48 driven from an electric motor 49. The fan 48 is connected at its discharge end with an air duct 50 which discharges into a header 51 connected to the air heater 40 composed of a plurality of horizontal flues. As best illustrated in Figures 1, 2 and 5, the air or super-heated steam to be heated to a drying temperature of 700° F. is passed through the air heater 40 and from there into a hot air header 52 which is in turn connected to a hot air distributing duct 53. The duct 53 serves to connect the header 52 with a drier header 54.

The novel drier 56 of our invention is adapted to be connected to the header 54 at one end of the drier, and this is preferably the incoming end for the sheets to be dried. Our drier has many important features, one of which is dividing the drier 56 into three separate chambers. An inner or drying chamber is formed as best illustrated in Figures 1 and 4, by dividing the drier with the inner drying chamber in the center and side air passages on each side of the inner drying chamber. The outer walls 57 and 58 of the drier 56 serve to provide the outer walls for the side air passages, and the walls 59 and 60 of the inner drying chamber serve to provide the inner walls of the side air passages. Partitions 61 at each end of the side air passages where the side air passages are adjacent to the drier header 54 serve to separate the side air return passages 35 from the drier header 54. The drier header 54 discharges the hot air or super-heated steam for drying the sheets into the inner drying chamber.

The side air passages formed respectively by the walls 57 and 59, and similarly 60 and 58, discharge into an outlet flue 62, as best illustrated in Figures 1 and 4. The air return duct 62 is suitably connected to the intake of the circulating fan 48 for the closed system of our novel drier system.

The inner drying chamber to which the tiers of sheets to be dried are suitably conveyed on a conveyor for each of its respective tiers, has at its end adjacent to where the sheets enter the conveyor at the drier header 54 a plurality of baffles 63 corresponding to the upper and lower side of each tier of the conveyor. The ends of the baffle 63 are suitably rounded as at 64 so that the hot air or super-heated steam entering into the inner drying chamber may circulate around the edges of the sheets which are being dried to thus thoroughly and evenly dry the sheets all over. A large baffle 65 serves to support the upper side of the drying chamber and also serves to discharge the super-heated steam or air across the top of the drying chamber adjacent to the upper sheet or tier of material being conveyed through the drying chamber. Conveyors 66, as illustrated in Figures 4 and 5 diagrammatically, are adapted to convey each tier of material which is being dried between the baffles 63 at the entering end of the drier 56. The baffles 63 on each side of the sheet as it enters the drier 56 serve to distribute the hot air or super-heated steam uniformly across the surfaces of the sheet but also serve to seal the drier from the outside atmosphere and are additionally provided with canvas flaps (not shown) to complete the sealing. Although any type of conveyor, as disclosed in the prior art, may be satisfactorily used in our drier system, we prefer,

however, to use the type of conveyor as disclosed in the U. S. patent to T. B. Munroe No. 1,598,980, granted September 7, 1926. It is also preferred to use a type of conveyor wherein the conveyor is entirely within the drying chamber so that no heat is lost by returning the conveyor from outside where the temperature is lower, thus causing a material heat loss. We also provide a large baffle 61 over the top of the inner drying chamber adjacent to the return air duct 62 so that the return air or super-heated steam is caused to flow along the side air passages formed adjacent to the inner drying chamber and also to flow across the top thereof in order to transfer as much heat as possible to dry the material as it is passed through the inner drying chamber. As our drier system is a closed system, the expansion due to the evaporation of the water from the board must be released, and this is accomplished by a vapor vent stack 69 at the end of the drier, and this stack is suitably controlled by a damper 70.

In the operation of our drier, the sheets from the sheet forming apparatus where they are felted from a water suspension of fiber and the like are formed in a continuous sheet and fed to the drier where they are cut into suitable lengths and elevated by a tipple to the various tiers of the drier. We prefer to cut the sheet as it comes from the sheet forming machine into lengths of from 150 to 250 ft. long and feed them into the drier in 8 tiers. It is also within the scope of our invention that the sheets may be cut into smaller sizes and placed on suitable racks, the racks then being suitably conveyed or pushed through the drying chamber of our drier. The movement of these sheets is comparatively slow, or say about as fast as one would walk at a slow gait. The actual speed, however, depends of course upon the temperature of the drying medium, the quantity of moisture to be evaporated and the drying efficiency of the medium.

As these sheets travel slowly and uniformly through the inner chamber of our drier, suitable hot air or preferably super-heated steam is fed into the drying chamber in the direction of travel of these sheets. The fluid for drying is forced through the air heater and heated to a temperature of substantially 700° F. whereupon it is discharged into the header and from there into the drying chamber. As the fluid, and especially we prefer to use super-heated steam, passes adjacent and along the upper and lower sides of each sheet, it picks up the moisture from each sheet and thoroughly dries the sheet without warping. The super-heated steam at a temperature of 700° F. readily vaporizes the water present in these fibrous sheets, so that they are dried rapidly and evenly, and especially when they contain a mixture of bagasse and wood fiber. The amount of water carried into the drier by these sheets may amount to as much as several hundred tons daily, so it is important that the heat remaining within the evaporated water shall be utilized as much as possible. For this reason the super-heated steam is recirculated over and over, and the excess water vapor evaporated from the sheets may be discharged through the stack 69 and passed through a suitable economizer in order to conserve the heat therein. The super-heated drying steam, which permeates the whole interior of the drier proper and which reduces in temperature to substantially 350° F. as the boards leave the drier, is divided and circulated along the outside of the

inner drying chamber through the side air passages and from there to the fan 48. The super-heated steam which has now reached a temperature of 350° F. because of the reduction in temperature due to the evaporation of the water within the sheet is reheated by means of the air heater 40 and is thus used over and over again being recirculated by the fan 48.

Owing to the presence of a water repellent on the fibers, the water derived from the forming machine is held more tenaciously by the sheets when the air is used as the drying medium than when steam is used and therefore an air drying process does not seem to satisfactorily reach the interior of a sheet and dislodge the water retained therein as does a steam drying process, as disclosed in our novel invention. Further, by the substantial exclusion of air from the drier, and by keeping the whole interior of the drying chamber filled with steam as above disclosed, it is found that the water is readily evaporated from the sheet in an expeditious, uniform and satisfactory manner not attainable by the use of air, so that the output of the mill is greatly increased.

The air heater 40 readily resupplies any heat that may be extracted from the super-heated drying steam when the water is thus evaporated from the interior of the sheets, and the air or super-heated steam heater also aids in maintaining a high temperature inside the drying chamber which varies from an inlet temperature of substantially 700° F. to an outlet temperature of 350° F.

It is obvious to those skilled in the art that we have disclosed a novel heating or drying system in combination with a steam plant so that the combined thermal efficiency of the steam plant and drying or heating system is materially increased.

It is also apparent from our disclosure that we have disclosed a novel air heater wherein hot products of combustion are tempered and reduced in temperature by passing waste flue gases into a mixing chamber before they enter the heat exchange means to heat the gas that does the drying without coming in contact with the combustion gases at any time.

It is also obvious that we have disclosed a novel method of controlling the thermal efficiency of a heating system comprising a steam plant having an economizer and a drying system having a source of combustion products, and an air heater, which comprises passing the flue gases of the steam plant through an economizer, passing a portion of the flue gases from the air heater for the drying system through the economizer, and tempering the combustion products to the air heater with the remaining portion of the flue gases from the air heater.

We have also disclosed a novel method of controlling the temperature within a drying system wherein products of combustion at a temperature of substantially 3300° F. are tempered and reduced in temperature to 1200° F. and the air or super-heated steam which is heated by the tempered products of combustion is heated to a temperature of 700° F. and then recirculated from the temperature of 350° F. to be reheated to 700° F. The temperature within the drier having a temperature of 700° F. is reduced to 350° F. by conveying the material to be dried thereto at a uniform rate, and returning the super-heated steam or air at a temperature of substantially 350° F. to the air heater to be reheated and recirculated. Whenever air is used in the

claims, it is to be understood that it is used generically and to broadly cover any suitable drying fluid or medium, such as super-heated water vapor or super-heated steam. Also, the specific temperatures recited are given by way of example only, are approximate, and will vary according to conditions of individual usage and are to be taken as indicative only.

It is obvious that those skilled in the art may vary the details of construction, the arrangement of parts and the mode of operation, without departing from the spirit of this invention, and therefore it is not desired to be limited to the foregoing disclosure except as may be required by the claims.

What is claimed is:

1. In a heating system forming a drying medium heating, water heating, and drying system, the combination of a drying system for drying moist fibrous insulation board and comprising a drier, an air and water vapor mixture heater comprising a mixing chamber and means generating hot gases for heating the air and water vapor mixture heater; a steam plant comprising a furnace, a boiler, and an economizer for heating processing water; means for circulating through the economizer the flue gases from the boiler, means for circulating through the economizer a portion of the flue gases from the means for heating the air and water vapor mixture heater whereby the overall thermal efficiency of the heating system is increased, means for tempering the hot gases from the means for heating the air and water vapor mixture heater whereby the temperature of the hot gases entering the air and water vapor mixture heater is reduced, and means for circulating heated air and water vapor mixture from the air and water vapor mixture heater through the drier in a closed circuit, whereby the moist fibrous insulating board is dried in an atmosphere of super-heated water vapor.

2. In a drying system for drying moisture carrying fabricated fiber board in an atmosphere of super-heated water vapor, the combination of a drier through which fabricated fiber board may be passed, an air and water vapor mixture heater comprising means for circulating a drying medium horizontally therethrough, means generating hot gases for heating the air and water vapor mixture heater, the air and water vapor mixture heater comprising means for circulating the hot gases downwardly through the air and water vapor mixture heater and transversely with respect to the drying medium, means comprising a closed system for circulating the drying medium comprising an atmosphere of super-heated water vapor through the drier and returning it to the air and water vapor mixture heater, and means for tempering the hot gases from the means for heating the air and water vapor mixture heater, whereby the gases entering the air and water vapor mixture heater are reduced in temperature.

3. In a hot air drying moisture carrying system for drying fabricated fiber board in an atmosphere of super-heated water vapor, the combination of a closed drying system comprising means through which moisture carrying fabricated fiber board may be passed, an air and water vapor mixture heater comprising means for circulating a drying atmosphere horizontally therethrough, and means for circulating the such drying atmosphere of super-heated water vapor through the drier and returning it to the air and water vapor mixture heater, a furnace adapted for supplying flue gases for heating the air and water vapor mixture heater, the air and water vapor mixture heater

comprising means for circulating the hot gases downwardly through the air and water vapor mixture heater and transversely with respect to the drying medium, and means for tempering the flue gases from the furnace whereby the flue gases entering the air and water vapor mixture heater are reduced in temperature.

4. The combination with a means for supplying flue gases at a substantially high temperature, of an air and water vapor mixture heater comprising means for circulating an atmosphere of super-heated water vapor horizontally therethrough in heat transfer relation with respect to the flue gases, a drier for drying fabricated fiber board in an atmosphere of super-heated water vapor, and means for circulating the atmosphere of super-heated water vapor from the air and water vapor mixture heater through the drier and through the air and water vapor mixture heater for re-heating and recirculation, the air and water vapor mixture heater comprising means for circulating the flue gases downwardly through the air and water vapor mixture heater and transversely with respect to the drying medium, and means for tempering the flue gases from the means for supplying flue gases whereby the flue gases entering the air and water vapor mixture heater are reduced in temperature.

5. The combination with a means for supplying flue gases at a substantially high temperature, of an air heater comprising means for circulating an atmosphere of super-heated water vapor horizontally therethrough in heat transfer relation with respect to the flue gases, means for tempering the flue gases comprising a mixing chamber intermediate the means for supplying the flue gases and the air and water vapor mixture heater, the air and water vapor mixture heater comprising means for circulating the tempered flue gases downwardly through the air and water vapor mixture heater and transversely with respect to the flow therethrough of the drying medium, a drier for drying fabricated fiber board in an atmosphere of super-heated water vapor, means for circulating the atmosphere of the super-heated water vapor from the air and water vapor mixture heater through the drier, and means for circulating a portion of the flue gases from the air and water vapor mixture heater into the mixing chamber whereby the flue gases entering the air and water vapor mixture heater from the means for supplying flue gases are reduced in temperature.

6. An air and water vapor mixture heater for a heating system comprising a mixing chamber, means operatively connecting the mixing chamber to a supply of combustion products, means for super-heating an atmosphere of water vapor connected to the mixing chamber comprising means for circulating the atmosphere of water vapor horizontally through the air and water vapor mixture heater and underneath the mixing chamber and means for circulating the combustion products from the mixing chamber down through the air heater and transverse with respect to the atmosphere of water vapor but in heat transfer relation, means for circulating the atmosphere of water vapor to be super-heated through the heater, and means for re-circulating a portion of the waste combustion products from the air and water vapor mixture heater to the mixing chamber, whereby the combustion products supplied to the mixing chamber are tempered.

7. In a closed heating system comprising a source of combustion products, the combination

of an air and water vapor mixture heater operatively connected thereto comprising a mixing chamber receiving the combustion products from the source therefor, means operatively connecting the mixing chamber to the source of combustion products, means for heating the air and water vapor mixture underlying the mixing chamber and connected to the mixing chamber and adapted to circulate the combustion products down from the mixing chamber through the air and water vapor mixture heater and in heat transfer relation with respect to the air and water vapor mixture to be heated and transversely with respect thereto, means for circulating air and water vapor mixture to be heated horizontally through the second mentioned means and through the closed heating system, means for re-circulating a portion of the waste combustion products exhausting from the air and water vapor mixture heater to the mixing chamber, and means for supplying cold air to the last mentioned means, whereby the combustion products supplied to the mixing chamber are tempered.

8. In a heating system comprising a closed circuit drier system, the combination of a furnace, a hot gas chamber connected to the furnace, an air and water vapor mixture heater supplying drying medium to a connected closed circuit drier and comprising a mixing chamber operatively connected to the hot gas chamber, damper controlled means for discharging the hot gases from the hot gas chamber to the atmosphere, and thermostatically controlled damper means between the hot gas chamber and the mixing chamber and actuated by the change in temperature of the connected atmosphere within the closed circuit drier system, whereby the air and water vapor mixture heater is protected from excessive temperature rises.

9. In a heating system comprising a closed drier system, the combination of a drier, a furnace, a hot gas chamber connected to the furnace for supplying hot gases, an air and water vapor mixture heater comprising a mixing chamber operatively connected to the hot gas chamber, the air heater also comprising means for the circulation of the atmosphere of the drier system horizontally therethrough, means for discharging a portion of the waste gases from the air heater to the mixing chamber whereby the hot gases from the hot gas chamber are tempered, the air heater comprising means for circulating the tempered hot gases downwardly through the air and water vapor mixture heater and transversely with respect to the atmosphere of the drier system circulated therethrough, means for discharging the remainder of the waste gases from the air and water vapor mixture heater to the atmosphere, and means for circulating the atmosphere of the drier system through the air and water vapor mixture heater to be heated.

10. In a heating system, the combination of a furnace, a hot gas chamber connected to the furnace for supplying hot gases, an air and water vapor mixture heater comprising a mixing chamber operatively connected to the hot gas chamber by a damper controlled passage, a drier operatively connected to the air and water vapor mixture heater, damper controlled means for discharging the hot gases from the hot gas chamber to the atmosphere, and thermostatically con-

trolled damper means between the hot gas chamber and the air and water vapor mixture heater for the drier and located in the aforesaid passage and actuated by the change in temperature of the atmosphere within the drier, whereby the material within the drier is protected from excessive temperature rises.

11. In a drying system, the combination of a source of combustion products, a hot gas chamber connected to the source of combustion products, an air and water vapor mixture heater operatively connected to the hot gas chamber by a damper controlled passage, a drier connected to the air and water vapor mixture heater, and thermostatically controlled damper means between the source of hot combustion products and the air and water vapor mixture heater for the drier and located in the aforesaid passage, whereby the material within the drier is protected from excessive temperature rises.

12. The combination with a source of combustion products and a drier, of an air and water vapor mixture heater comprising a heat exchange means operatively connected to the drier and

means for circulating the atmosphere of the drier to be heated through the heat exchange means, said air and water vapor mixture heater comprising a mixing chamber connected to the heat exchange means and said source of combustion products, means for circulating a portion of the waste combustion products from the heat exchange means to the mixing chamber, whereby the combustion products entering the mixing chamber are tempered, and the air and water vapor mixture heater comprising means for the circulation of the atmosphere of the drier horizontally therethrough and means for circulating the tempered combustion products downwardly therethrough and in heat transfer relation with respect to the drier atmosphere.

13. The combination with a source of combustion products and a drier, of an air and water vapor mixture heater comprising a heat exchange means operatively connected to the drier the heat exchange means comprising horizontal passageways and means including passages for circulation of air and water vapor mixture to be heated through the heat exchange means whereby the air and water vapor mixture to be heated is forced horizontally through the passages of the heat exchange means, said air and water vapor mixture heater comprising a mixing chamber operatively connected to the heat exchange means and said source of combustion products by a damper controlled passage and mounted over the heat exchange means, means for circulating a portion of the waste combustion products from the heat exchange means to the mixing chamber whereby the combustion products entering the mixing chamber are tempered and are caused to pass through the mixing chamber downwardly across the heat exchange means, and thermostatically controlled damper means between the source of combustion products and the air and water vapor mixture heater for the drier and located in the aforesaid damper controlled passage and actuated by the change in temperature of the atmosphere circulated through the drier, whereby the air and water vapor mixture heater is protected from excessive temperature rises.
